UNITED STATES PATENT OFFICE.

JOHN ALLISON, OF DRAVOSBURG, PENNSYLVANIA, ASSIGNOR TO PITTSBURGH STEEL FOUNDRY COMPANY, OF GLASSPORT, PENNSYLVANIA, A CORPORATION OF PENNSYLVANIA.

DRAFT-GEAR CARRIER.

1,214,111.

Specification of Letters Patent. Patented Jan. 30, 1917.

Application filed April 13, 1915. Serial No. 21,049.

To all whom it may concern:

Be it known that I, JOHN ALLISON, a resident of Dravosburg, in the county of Allegheny and State of Pennsylvania, have invented a new and useful Improvement in 5 Draft-Gear Carriers, of which the following is a specification.

This invention relates to draft gear carriers for railway cars, and more particularly to cast steel draft gear carriers for 10 cars having wooden center sills located above the body bolster, although it may be also applied to cars with metal sills.

The object of the invention is to provide 15 a draft gear carrier of this kind, which can be made of a single integral member employing a minimum amount of metal and thoroughly reinforced and strengthened throughout, so that it is strong and rigid 20 and very light for its strength; one which distributes the strains on the car frame between the end sill, center sills, body bolster and other framework; one which has a rearward extension from the body bolster in the 25 form of a strong, hollow box girder whose rear end portion may be in the same horizontal plane with the body bolster and is attached to the center sills, so that it transmits directly the longitudinal pull or thrust 30 and the upward thrust directly to the car frame; one which can be adapted for various types of body bolster and draft gear; and one which can be inserted into place without requiring removal of the trucks.

35 Other objects of the invention are in part obvious and in part will appear more in detail hereinafter.

The invention comprises the draft gear carrier hereinafter described and claimed.

40 In the drawings, Figure 1 represents a plan view of one form of draft gear carrier embodying the invention; Fig. 2 is a longitudinal sectional elevation, of a similar draft gear carrier, the section being taken 45 on a plane corresponding to the section line 2-2 in Fig. 1, and showing a modified form of king pin opening; Fig. 3 is a cross section on the line 3-3, Fig. 2; Fig. 4 is a half cross section on the line 4-4, Fig. 2; Fig. 5 is a 50 half end view showing the support for the movable carrier bar; Figs. 6 and 7 are detail views of the connection to the bolster and showing a modification; Fig. 8 is a plan view corresponding to Fig. 7; and Fig. 9 55 is a detail view showing a modification.

The draft gear carrier shown in the drawings is a hollow cast metal member formed of a single piece of metal and having many of the characteristics of a box girder, so that it is exceedingly strong and rigid and 60 yet is of minimum weight. The front portion of said carrier has two opposite vertical side walls or members 1 which are spaced apart to receive the draft gear, not shown, but which may be of any suitable type. If 65 the draft gear is of the usual spring and follower plate construction the side walls 1 of the carrier are preferably provided on their inner faces with inwardly projecting lugs or ribs 2 for guiding the springs and 70 maintaining them in central position in the carrier. In some types of draft gear laterally extending spring supporting devices are utilized, and to accommodate such gears the side walls 1 may be provided with central openings 8, so that the gear supporting members may extend through or outside of 75 the side walls or members of the draft carrier. The side walls may also be provided with downwardly extending integral pockets 80 3 to receive transverse gear supporting bars 4. Said walls are also provided with inwardly extending portions 5 for confining the front and rear follower plates, as is usual, and said inwardly extending walls 85 6 may be provided with depending pockets 7 for receiving the longitudinal gear supporting bars 8.

The follower plates are confined against upward movement in the draft gear carrier by inwardly extending horizontal walls or flanges 9, which form a housing for the draft gear and partially inclose the same. These horizontal walls, at or near their front ends, are connected by an integral transverse member 10, which forms a cross connection between the side members of the carrier and reinforces and strengthens the same. Particularly when the draft gear pocket is long the resistance to spreading 100 of the side arms or members 1 may be further increased by one or more supplemental integral cross tie members 10^a, one of which is shown in Fig. 1. The transverse member 10 has a vertically disposed web or wall 105 lying behind the rear face of the usual end sill 11, so that pulling strains transmitted to the draft gear carrier are distributed in part to the end sill and the car framework of which it forms a part. To enable the 110

5 draft gear carrier to be inserted from beneath without removing the trucks, the front wall of the transverse member 10 may be inclined forwardly and downwardly, as shown at 12, the end sill 11 being beveled to correspond. When the draft gear carrier is pushed up into place over the body bolster the transverse member wedges in behind the end sill and is therefore very solidly 10 connected to the car frame. The same effect can also be obtained without resorting to an inclined wall or beveling the end sill by inserting a shim 13 between the end sill and transverse member 10 after the draft gear 15 carrier is pushed into place, as shown in Fig. 9.

20 The draft gear carrier is also arranged to transmit pulling strains to and receive buffing strains from the usual end buffer 14, located in advance of the center sill 11. This end buffer is shown as an integral portion of the draft gear carrier itself, so that it forms an additional strengthening cross tie, but it may be a separate member riveted 25 or bolted thereto and to the end sill, as at 14^a, in Fig. 9. In this case the side members 1 of the draft gear carrier are provided with vertical shoulders 15 lying behind the end buffer. Consequently, in both 30 forms of carrier buffing shocks are transmitted directly from the end buffer to the carrier and distributed to the car frame, as will be readily understood.

35 The front portions of the side walls 1 of the carrier are somewhat closer together than those portions opposite the spring pocket therebetween, as is usual. These portions of the side walls may be provided with longitudinal slots or openings 16 for 40 receiving the transverse draft gear keys for securing the draw bar to the draft gear. Also, near their front ends the side walls or members 1 of the draft gear carrier are provided with longitudinally spaced, inwardly 45 extending integral brackets 17 to receive a suitable swinging support for the movable carrier bar. As shown, this support is a transverse bar 18 having bifurcated hook-shaped end members 19 carried by the lower 50 cross bar 20 of an I-shaped link 21 having an upper cross bar 22 fitting in the brackets 17. The cross bar 18 is thus capable of swinging from side to side with the carrier bar but prevents it from dropping down.

55 This draft gear carrier is intended particularly for use with cars embodying the usual wooden center sills, such as indicated at 23. The upper horizontal walls 9 of members 1 are therefore provided with upwardly extending parallel vertical flanges 24 provided with openings for receiving horizontal bolts passing through the center sills. The draft gear carrier is also provided with a rearward extension 25, which is generally 60 of the form of a hollow box girder, nar-

rower than the front portion of the carrier, so that it fits between the two wooden center sills and whose side walls 26 are continuations of the walls 24. These side walls 26 are also provided with horizontal bolt holes 70 for attaching the carrier to the center sills, said side walls being connected by upper and lower cross webs or members 27 and 28. It curves upwardly from the spring pocket to a position above the body bolster, and beyond the body bolster preferably curves 75 downwardly so that its rear end portion is in substantially the same horizontal plane as the body bolster. Consequently, pulling strains are transmitted in a straight line, but no 80 special modification of the body bolster is necessary. The rearward extension 25, on its opposite sides, is provided with outwardly extending horizontal flanges 30 having bolt holes for securing them to the bottom faces 85 of the center sills, and said horizontal flanges may also have portions 31 above the body bolster provided with openings for riveting or bolting them thereto. Bolt holes 33 may also be provided in the horizontal portion of 90 the rearward extension above the body bolster. Consequently, the draft gear carrier may be very firmly and rigidly secured both to the center sills and body bolster.

95 The upper and lower horizontal walls of the rearward extension, above the body bolster, are preferably also provided with aligned openings 34 for receiving the king pin, and if desired, these openings may be oblong or elongated, as at 34^a, Fig. 2, to 100 adapt the carrier for different types of body bolster and for different distances between the body bolster and the end of the car. For example, Figs. 2 and 6 indicate respectively at 29 and 36 the upper plates of two 105 different forms of body bolster, and having openings for the king pin at opposite ends of the elongated openings 34. In Fig. 2 the lower horizontal web of the rearward extension 25 is provided with downwardly extending front and rear transverse shoulders, marked 37 and 38 respectively, which abut 110 against the front and rear faces of the body bolster, for transmitting longitudinal strains thereto. The lower face of the rearward extension of the draft gear carrier may also be provided with a number of depending lugs or bosses 40, as in Figs. 6 to 8, which 115 can be utilized for transmitting the thrust of the draft gear carrier to a narrower bolster, and hold the bolster in the proper position for receiving the king pin. By properly locating these lugs the carrier may be adapted for any type of body bolster, and may be subsequently adapted for a wider bolster by chipping off or otherwise removing first one set and then the other set of said 120 lugs.

125 The rear end portion of the draft gear carrier is provided with a transversely ex- 120

tending vertical web portion 41 connecting its side walls. The rear end portion 42 of the upper horizontal wall of said member may be riveted or otherwise secured to a suitable transverse member 43 lying under and secured to the center sills 23. Consequently, the upward thrust of the rear end of the draft gear carrier is transmitted to the center sills. The vertical web 41 may be taken advantage of for transmitting the longitudinal thrust of the draft gear carrier to the center sills, by making the transverse member 43 an angle iron or Z-bar whose vertical web receives the thrust from the web 41 and also abuts blocks 23^a fastened to the center sills.

The rear extension of the draft gear carrier is open on its bottom, its side walls being connected at the bottom only by the transverse member 28 near the spring pocket and also above the body bolster, the bottom openings therein providing access to the interior of the carrier for fastening attachments thereto. Beyond the body bolster the downwardly extending rear end portion of the carrier may also be provided with horizontal outwardly extending flanges 44 for attachment to the lower faces of the center sills.

To adapt the carrier for use with steel center sills which do not extend the full length of the car the side walls of the rearward extension may also be provided on their outer faces with lugs or projections 50 forming vertical shoulders to abut the ends of said sills and transmit longitudinal strains thereto.

This draft gear carrier is very light for its strength and consequently can be made at comparatively low cost. It has all the usual functions of draft gear carriers and in addition distributes the strain over the entire car frame so that the wear and tear thereon is reduced. It may be lifted into place from beneath without removing the car trucks, by pushing the rearward extension up over the body bolster and after it has been pushed fully back, lifting the front portion of the draft gear carrier and securing it to the center sills. Consequently repairs and replacements are readily effected without special equipment. The draft gear carrier also may be adapted for any style of car or any type of draft gear.

It will, of course, be understood that the invention is not limited to the precise form of carrier shown in the drawings, but admits of considerable modification within the scope of the appended claims without departing from the spirit of the invention.

What I claim is:—

1. A draft gear carrier, comprising side members spaced to receive the draft gear therebetween, and a rearward extension integral with said side members and extend-

ing over and beyond the body bolster, the rear end of said extension being in substantially the same horizontal plane as the body bolster, and a laterally extending member connected to said extension and arranged to transmit the upward thrust of the carrier to the center sills of the car.

2. A draft gear carrier, comprising integral side members spaced to receive the draft gear therebetween, said side members being provided with integral inwardly extending horizontal flanges lying immediately adjacent the top edges of the follower plates and forming the upper guide for said follower plates and serving as a housing enclosing and protecting the same.

3. A draft gear carrier, comprising integral side members spaced to receive the draft gear therebetween, said side members being provided with inwardly extending horizontal flanges forming a top guide for the follower plates, in combination with removable horizontal bars forming the lower guide for said follower plates.

4. A draft gear carrier, comprising integrally connected side members spaced to receive the draft gear therebetween, longitudinally extending bars directly supporting the draft gear, and integral depending bracket members on the lower portions of said side members having openings for receiving said longitudinal gear supporting bars.

5. A draft gear carrier, comprising integrally connected side members spaced to receive the draft gear therebetween and provided in the horizontal axial plane of the draft gear with openings to receive transversely extending spring carrying devices.

6. A draft gear carrier having at one end side members spaced to receive the draft gear therebetween and provided with a rearwardly extending integral hollow member passing up over and downwardly beyond the body bolster, said member lying between the center sills.

7. A draft gear carrier, comprising integrally connected members spaced to receive the draft gear therebetween, and a rearwardly projecting hollow extension lying between the center sills and passing over and beyond the body bolster, said side members and the side walls of the rearward extension being arranged for attachment to the center sills.

8. A draft gear carrier, comprising integrally connected side members spaced to receive the draft gear therebetween, and a rearwardly projecting hollow extension passing over and beyond the body bolster, said carrier and its extensions being provided with horizontal flanges for attachment to the bottom surfaces of the center sills.

9. A draft gear carrier, comprising integrally connected side members spaced to re-

ceive the draft gear therebetween, a rearwardly projecting hollow extension passing above and beyond the body bolster, the upper and lower horizontal members of said extension above the body bolster being provided with elongated openings for adjustably receiving the king pin.

10. A draft gear carrier, comprising integrally connected side members spaced to receive the draft gear therebetween, a rearwardly projecting hollow extension passing above the body bolster, the lower wall of said extension being provided with transversely extending shoulders arranged to abut 15 the body bolster, and projections on the lower face of the extension between said shoulders and forming shoulders for a narrow body bolster.

11. A draft gear carrier, comprising integrally connected side members spaced to re-

ceive the draft gear therebetween, and a hollow rearwardly projecting extension passing beyond the body bolster, said extension being open on its lower side between the draft gear and bolster, and an integral 25 tie member connecting the lower portions of the side walls of said extension.

12. A draft gear carrier, comprising side members spaced to receive the draft gear therebetween, a rearward extension integral with said side members and passing above the body bolster, and an integral tie member connecting said side members above the draft gear.

In testimony whereof, I have hereunto set 35 my hand.

JOHN ALLISON.
